UNITED STATES PATENT OFFICE

SVEN DUNER, OF WHEATON, ILLINOIS

WATER CLOSET

Application filed May 26, 1930. Serial No. 455,687.

This invention relates to water closets provided for use in railway cars and like locations, and while it will be hereinafter described as embodied in a water closet like that shown in the co-pending application of John C. Duner for U. S. Letters Patent, Serial No. 375,243, filed July 1, 1929 which has matured into a Patent No. 1,845,252, it will be readily apparent that from certain aspects the invention has broader and more general application.

Toilets of this sort are ordinarily provided with a dump pan adapted to be dropped in flushing with a resultant upflow of air frequently occurring with considerable velocity, and producing a blast directed upwardly through the toilet or closet. In the co-pending application above referred to, a draft member is disclosed for sealing the closet outlet, as an incident to the flushing of the toilet. This draft member, preferably and in accordance with the disclosures of said co-pending application moves into sealing or closed position during the initial opening movement of the dump pan, and prior to the breaking of the water seal.

The instant invention has for its principal object the construction and arrangement of the parts of a water closet of the character described which will permit the draft member to remain in full opened position when the dump pan is dumped to the end that a free open passage-way may be provided upon occasion for the flushing and cleaning of the toilet.

This invention has also for a principal object, the provision of a water closet of the character described, wherein the draft member may optionally be operated conjointly with the dump pan, and also wherein the dump pan may be moved to an open position while the draft member remains open to facilitate flushing and cleaning of the closet.

Another important object of the invention is the provision of a water closet wherein the dump pan is positively moved by a lever or otherwise to a dumping position, and thereafter is returned by a separately yielding or gravity device to a closed position, and also to so construct and arrange the

parts that the gravity controlled operation is or may be independent of the positively induced movement. The invention contemplated in this regard a provision of a gravity return for the dump pan, so constructed and arranged that it may be supported in elevated position with the dump pan open, to facilitate cleaning of the toilet.

Another important object of the invention is the provision of a water closet provided with oppositely operating dump pan and draft members, controlled normally by a single manipulative device, the parts of which will be so constructed and arranged that the dump pan may be moved to dumping position by means which are independent of said control and which provide return of parts to normal position after dumping through said control.

Numerous other objects and advantages of the invention will be apparent as it is better understood from the following description, which, taken in connection with the accompanying drawings, discloses a preferred embodiment thereof.

Referring to the drawings,

Figure 1 is a side elevation, parts being shown in section of a railway closet embodying the present invention;

Fig. 2 is a view partially in front elevation, and partially in section, showing certain details of construction;

Fig. 3 is a transverse partial sectional view on an enlarged scale, taken substantially on the line 3—3 of Fig. 4; and

Fig. 4 is an enlarged detailed perspective of the connection between the manually operable positive control and the dump pan shaft.

For the purpose of illustrating the present invention the drawings show a closet of the character usually provided in Pullman and railway cars. As shown on the drawings this closet comprises an outer stand or support 11 of usual or preferred type, which supports a closet bowl 12 at the upper end. The closet bowl 12 is provided with an outlet 13 at the bottom, this outlet being normally closed by a water containing dump pan 14, which is pivoted upon a shaft 15, journalled as shown

in Fig. 2 in opposite sides of the support 11. The shaft 15 is embraced adjacent its left-hand end viewing Fig. 2 by one end of an arm 16, the other end of which is pivoted 5 at 17 to an upwardly extending link 18, in turn connected at this upper end at 19 to a manually operable lever 21 pivoted at 22 to a suitable valve control of the water-flushing mechanism indicated generally at 23. Particular description of this water-flushing mechanism is not thought necessary since it forms no part of the present invention.

The shaft 15 is provided at this end beyond the arm 16 with a fixed collar 24, upon which 15 is formed a shoulder or stud 25. This shoulder or stud 25 is arranged above a lug or projection 26, formed integrally with the arm 16 so that lifting of the arm through the link 18 and lever 21 will cause the projection 26 20 to engage the lug 25 and rotate the shaft 15 to swing the dump pan 14 downwardly from sealing to dumping positions.

The opposite end of the shaft 15 is provided with a gravity member consisting of a weight 25 27, which is provided with an arm 28 secured upon the end of the shaft 15 by a set screw or lock nut 29. It will be noted that the arrangement is such that the weight tends to move the dump pan up into dumping position, so that movement of the lever 24 to accomplish dumping requires lifting of the weight.

A draft member 31 is provided to close the closet outlet 32, and this draft member is oppositely movable with the dump pan, closing movement of the draft member being preferably accomplished during the initial opening movement of the dump pan. The draft member 31 is provided with arms 33, fixed respectively upon the shafts 34 arranged horizontally through bearings 35 in the base of the stand 11. The shaft 34 at the left of the closet viewing Fig. 2 is provided with a fixed collar 36, from which an arm 37 extends upwardly, and is provided with a laterally extending pin 38. The pin 38 is adapted to engage a cam 39. The cam 39 is carried by an arm 41 clamped about a sleeve extension 42 of the arm 16, so that the cam moves with the arm 16, and independently of oscillation of the shaft 15, except when the projection 26 in its movement causes conjoint shaft movement through the lug 26. Particular description of the cam 39 and its connection 55 with the arm 37 is not thought necessary since it is fully explained in the co-pending application already mentioned.

From the foregoing it will be apparent that normally the draft member moves currently and opposite to the pan in dumping. When, however, it is desired to arrange the dumping pan in dumping position with the draft member remaining in open position, it is only necessary to lift the gravity member or weight 27 to the elevated posi-

tion it assumes, when the dumping of the toilet is accomplished through the manipulation of the control lever 21. Thus raised, free opening is provided through the closet for flushing with a hose or other cleaning. None of the parts need be disconnected, and none of them need be removed to accomplish this result.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A water closet, comprising a closet bowl supported above its outlet, a dump pan positioned beneath said bowl and adapted to swing from a sealing position downwardly to a dumping position, a draft member located beneath said dump pan, means for causing conjoint movement of said dump pan and said draft member to close said draft member as an incident to the dumping of said dump pan, and means for moving said dump pan independently of movement of said draft member.

2. A water closet, comprising a closet bowl supported above its outlet, a dump pan positioned beneath said bowl and adapted to swing from a sealing position downwardly to a dumping position, a draft member located beneath said dump pan and conjointly operable with the opening movement of said dump pan for sealing the closet outlet, means for conjointly moving said dump pan and said draft member to dump said dump pan and close said draft member, a separate means for returning the parts to normal position, said means being adapted to move said dump pan to dumping position independently of said draft member.

3. A water closet, comprising a closet bowl supported above its outlet, a dump pan positioned beneath said bowl and adapted to swing from a sealing position downwardly to a dumping position, an oppositely operable draft member for sealing the closet outlet during dumping, manually operable connections between said dump pan and said draft member for controlling the conjoint movement thereof, said connections comprising a member attached to said dump pan and yieldingly pressed for the movement controlled by said connection.

4. A water closet, comprising a closet bowl supported above its outlet, a dumping pan positioned beneath said bowl and adapted to swing from a sealing position downwardly to a dumping position, an oppositely operable draft member for sealing the closet

outlet during dumping, manually operable connections between said dump pan and said draft member for controlling the conjoint movement thereof, said connections comprising a member attached to said dump pan and yieldingly pressed for the movement controlled by said connection, said member being movable independently of movement controlled by said connection to accomplish movement of the dump pan into dumping position without accompanying movement of said draft member.

SVEN DUNER.
